CARTON AND BLANK FOR FORMING THE SAME

Filed Sept. 3, 1932

UNITED STATES PATENT OFFICE

2,019,538

CARTON AND BLANK FOR FORMING
THE SAMEHenry Kondolf, New York, N. Y., assignor to
Southern Kraft Corporation, New York, N. Y.,
a corporation of Delaware

Application September 3, 1932, Serial No. 631,647

8 Claims. (Cl. 229—16)

This invention relates to an improvement in paper packages or cartons, suitable for packing fruit, vegetables and the like for shipment and sale, and especially adapted to display the contents 5 of the carton when offered for sale.

In my prior U. S. Patent No. 1,741,369, granted December 31, 1929, it is pointed out that in packages of the character recited above, it is extremely desirable and advantageous to confine the contents of the package under moderate pressure sufficient to cause the cover to bulge more or less, thereby not only firmly securing and preventing injury to the fruit or other commodity thus packed, but insuring that the carton will present a 10 fully and tightly packed appearance when offered for sale, in spite of such shrinkage of the total volume of the contents as may occur between the time the carton is packed and the time of sale. No intent to deceive is contemplated or possible, as 15 the commodity packaged is generally sold on a bulk weight or count basis, nevertheless, successful merchandising demands a package having a well-filled, bulged appearance.

This object is attained in my aforesaid patent by 20 providing a cover of such design as to provide a malleable display panel adapted to be raised above the outer edges of the cover.

My present invention contemplates and has for 25 an object the provision of an improved carton of the character indicated, capable of being formed from a single continuous sheet of paper, and a blank therefor.

A further object of my invention is to provide a 30 carton and blank therefor of the character indicated, having provision for filling the same from the bottom as well as for adjusting the interior volume of the carton in a simple and efficacious manner, for ventilating the contents of the carton, for holding the contents securely in place, 35 and for facilitating face packing of the carton with fruit of different sizes and in different quantities.

A still further object of my invention is to provide a carton and blank therefor of the character indicated, having improved means for displaying the contents thereof.

My invention has for further objects such other 40 improvements and advantages in construction and detail as may hereinafter be found to obtain.

In order that my invention may clearly be set forth and understood, I now describe, with reference to the accompanying drawing, a preferred form and manner in which my invention may be embodied and utilized. In the drawing,

Fig. 1 is a plan view of a pre-formed sheet of paper or blank adapted to be folded to form a carton of the character indicated hereinabove;

Figs. 2 and 3 are bottom elevational and sectional views, respectively, of a carton formed from

the blank illustrated in Fig. 1, Fig. 3 being taken along the line III—III of Fig. 2;

Fig. 4 is a perspective view of a portion of the carton as illustrated in Figs. 2 and 3;

Figs. 5 and 6 are plan and sectional views, respectively, of a carton formed from the blank illustrated in Fig. 1, Fig. 6 being taken along the line VI—VI of Fig. 5 and illustrating a modified manner of folding the blank of Fig. 1 to provide a closure for the carton; and

Fig. 7 is a perspective view of a portion of the carton as illustrated in Fig. 6.

Similar reference numerals designate similar parts in the several views of the drawing.

As will be apparent from the drawing, my carton is formed from a single continuous sheet of paper of suitable character, having a cover panel A, side panels B, C, D and D', insert flaps E, E', F and F', and a bottom panel G.

The cover panel A is defined by score lines 1, 2, 3 and 4, forming a rectangle, the corresponding sides of which also form sides of the side panels B, C, D and D', respectively. Inwardly of the score lines 1, 2, 3 and 4, the cover panel A is provided with perforations or cuts 5, 6, 7 and 8 which, together with a score line or cut 9, define a malleable display panel 10 surrounded by a border or marginal section 11, the latter preferably cut away as at 12 to permit the insertion of a finger for the purpose of raising the display panel 10.

The principal corners of the display panel 10 are joined to the corresponding outer corners of the panel A by diagonal score lines 13.

For the purpose of protecting and retaining the contents of the carton when the display panel 10 is thus raised, I provide a sheet 16 of "Cellophane" or other transparent or translucent material, of a size and shape intermediate those of the display panel 10 and the entire cover panel A. This "window" sheet 16 is attached to that surface of the cover panel A destined to become an interior surface of the carton, preferably by means of a substantially continuous strip 18 of adhesive material which surrounds the display panel 10.

The side panel B adjoining the cover panel A along the score line 1, terminates at score lines 17 and 18 marking the junctures of the panel B with the side insert flaps E and E', respectively.

Similarly, the side panel C terminates at score lines 19 and 20 marking the junctures of the panel C with the side insert flaps F and F', respectively.

Preferably, the side panels D and D' are separated from the flaps E and F, and from E' and F', respectively, by tapered cuts 22, and the score lines 17 and 18, as well as 19 and 20, are somewhat convergent, thereby providing for a carton of tapered form, as will be apparent from inspec-

tion of the several figures and the descriptive matter hereinbelow.

The bottom panel G adjoins the side panel C along a score line 25, parallel to the score line 5 2, and while of generally rectangular shape, is preferably provided with diagonal corner cuts 26, for a purpose to be recited hereinbelow.

A score line 27 is provided, parallel to and relatively closely spaced from the score line 25.

10 Parallel score lines 28 and 29 are also provided near the opposite side of the panel G. One or more, preferably two, cut-out portions 31 are provided in the panel G, one side of each of which portions 31 coincides with or forms an extension 15 of the score line 28, while the ends of the cut-out portion or portions 31 are connected to the score line 29 by cuts 32, preferably although not necessarily, located at right angles to the score lines 28 and 29, thereby forming a flap or flaps 20 33. Preferably, the score line 29 does not extend across the flaps 33, but merely connects the sides of the flaps 33 to the sides of the box and to each other, as shown, so that the flaps 33 are not separated by any score line from that portion of the 25 panel G lying beyond the score line 29.

When my carton is to be formed and filled, the insert flaps E, E', F and F' are first bent at substantially right angles to the corresponding side panels B and C along the score lines 17, 18, 19 30 and 20, respectively, and the side panels B and C are then bent along the score lines 1 and 2, respectively, to substantially right angles with respect to the cover panel A until the upper edges of the insert panels E, E', F and F' coincide with 35 the score lines 3 and 4. The side panels D and D' are then bent along the score lines 3 and 4 respectively, until they meet the insert panels E, F, E' and F', and the panels D and D' are then fastened by means of staples 40 or other suitable 40 fastening means to the adjacent insert flaps E, F, E' and F', respectively. The carton is thus formed and ready to be filled.

I have found that the mere act of forming and 45 securing the carton, as hereinabove described, tends to cause the cover panel A to bulge upwardly to some extent, slight bends being made along the score lines 12, thus raising the display panels 10 above the outer edges of the cover panel A. This bulge is further accentuated, however, 50 when the carton is packed.

In the event that the fruit or other commodities placed within the carton are of sufficient bulk to well fill the carton, the bottom panel G is bent along the score line 28, the portion of the 55 panel G lying beyond the score line 28 being turned inwardly and placed inwardly of and adjacent to the side panel B, to which it is then fastened by means of staples 41 or other suitable fastening device. The cut-out portions 31 provide for insertion of a portion of the stapling instrument.

The bottom panel G is so positioned with respect to the remaining portions of the carton 60 that it acts through the medium of the contents of the carton to create or accentuate the bulge in the cover panel, thereby raising the display panel 10 above the outer edges of the cover panel A and giving the carton a well filled appearance. This position is illustrated in Figs. 6 and 7.

70 In the event, however, the fruit is small or the bulk thereof does not well fill the carton, the bottom panel G is bent sharply along the score line 29 to turn the flaps 33 inwardly of the carton as shown in Figs. 3 and 4. In this instance sufficient bending is permitted at the score lines 27 and 28

to provide for this difference from the position shown in Figs. 6 and 7 and to permit raising or lowering the principal portion of the bottom panel G to such a position as to cause the contents of the carton to be firmly pressed upwardly 5 against the cover panel A.

In this position that portion of the bottom panel G lying beyond the score lines 29 acts as an additional support together with the flaps 33, forming extensions thereof, to maintain the bottom panel 9 in the desired position. Staples 41 are used as before, except that in this instance these are preferably located in the flaps 33.

It will be noted that with the bottom panel G thus closed and fastened to the side panel B as 15 at 41, the beveled corners 26 provide ventilating spaces 42 in the lower corners of the carton which permit circulation of air and maintain the fruit or other contents in a fresh condition. It will further be observed in Figs. 3 and 6 that the 20 shape of the cut-out portions 22 provides small ventilating spaces 43 located in the upper and outer corners of the carton which, while small, are nevertheless adapted to cooperate with the ventilating spaces 42 to permit circulation of air 25 through the contents of the carton.

My carton and the blank from which it is formed are preferably manufactured from paper or fibre of sufficient strength and rigidity to prevent injury to the contents thereof under the ordinary conditions of shipment and storage, but I prefer to employ what is generally known as 30 double-faced corrugated kraft board.

When the filled carton is placed on display and offered for sale the display panel 10 is readily 35 raised by inserting a finger through the opening 12 between the display panel 10 and the "Cellophane" window sheet 15 and bending the display panel 10 upwardly along the score line 9. In this manner a prospective purchaser is afforded 40 a good view of the contents of the carton without permitting the latter to become soiled or otherwise damaged.

The display panel 10 may be completely detached, if so desired, this being facilitated by 45 making the score line 9 of such character as to permit detachment of the panel 10 along the score line 10 as well as along the score lines 5, 6, 7 and 8.

If desired, the bottom panel G may also be 50 provided with a mutilatable display panel similar to the panel 10, and the same is true of the other sides of the carton, more particularly the panels B and C. Each of said display panels is preferably provided with a window pane of "Cellophane" or other transparent material.

In the event that several of the sides of the carton are thus provided with mutilatable display panels, I may provide a single panel of "Cellophane" and the like, which panel may cover 60 substantially the entire blank, thereby forming in substance, when the carton is formed and the display panels removed, a Cellophane bag having a structural outer casing supporting the same but not seriously impairing the view of the 65 contents.

While, for packaging fresh fruit and vegetables, I prefer to so form the blank and carton that the latter will be tapered, as shown in the drawing, for many other purposes, a tapered form 70 is unnecessary, and the carton may then be made rectangular in shape.

It will therefore be obvious to those skilled in the art that my invention is susceptible of considerable modification in detail without de- 75

parting from the essential teaching thereof and is therefore not limited to the details of the preferred example given hereinabove by way of exemplification and illustration, but may variously be embodied within the scope of the claims hereinafter made.

I claim:

1. A container formed of a continuous sheet of paper or analogous material, having a cover panel provided with a central portion adapted to be raised above the outer edges of the cover panel, panels attached to said cover panel bent to form sides substantially at right angles to said cover panel, and a bottom panel connected along one side to and forming an extension of one of said side panels being bent along the juncture of said bottom panel and the side panel to which it is connected and fastened to another of said side panels in such position as to act upon the contents of the container to raise the central portion of said cover panel above the outer edges thereof, said bottom panel having a score line forming a bend substantially parallel to the juncture of said bottom panel and the side panel to which it is connected and adapted to permit a variation in the position in which said bottom panel is fastened to said other side panel.
2. A container formed of a continuous sheet of paper or analogous material, having a cover panel provided with a central portion adapted to be raised above the outer edges of the cover panel, panels bent to form sides substantially at right angles to said cover panel, and a bottom panel connected along one side to and forming an extension of one of said side panels and bent along the juncture of said bottom panel and the side panel to which it is connected, said bottom panel having a pair of score lines spaced from each other and from a side thereof, and cuts defining a flap adapted to be bent substantially at a right angle to the principal panel of said bottom panel for fastening to one of said side panels.
3. A container formed of a continuous sheet of paper or analogous material, having a cover panel provided with a central portion adapted to be raised above the outer edges of the cover panel, panels attached to said cover panels adapted to be bent to form sides substantially at right angles to said cover panel, and a bottom panel connected along one side to and forming an extension of one of said side panels adapted to be bent along the juncture of said bottom panel and the side panel to which it is connected, said bottom panel having an end portion having an inwardly extending flap and score lines extending across the panel at the juncture of said end portion and said flap and at least one score line extending across said panel intermediate said first-mentioned score lines and the juncture of said bottom panel and the side panel to which it is attached.
4. A container formed of a continuous sheet of paper or analogous material, having a cover panel provided with a central portion adapted to be raised above the outer edges of the cover panel, panels attached to said cover panel bent to form sides substantially at right angles to said cover panel, and a bottom panel connected along one side to and forming an extension of one of said side panels being bent along the juncture of said bottom panel and the side panel to which it is connected and fastened to another of said side panels in such position as to act upon

the contents of the container to raise the central portion of said cover panel above the outer edges thereof, a score line extending across said bottom panel inwardly of and adjacent to said first mentioned score lines and a second score line extending across said panel inwardly of and adjacent to the score line defining the juncture between said bottom panel and the side panel to which it is attached.

5. A container formed of a continuous sheet of paper or analogous material, having a cover panel provided with a central portion adapted to be raised above the outer edges of the cover panel, panels attached to said cover panel adapted to be bent to form sides substantially at right angles to said cover panel, and a bottom panel connected along one side to and forming an extension of one of said side panels adapted to be bent along the juncture of said bottom panel and the side panel to which it is connected, said bottom panel having an end portion having an inwardly extending flap and score lines extending across the panel at the juncture of said end portion and said flap and at least one score line extending across said panel intermediate said first-mentioned score lines and the juncture of said bottom panel and the side panel to which it is attached, said bottom panel also having a cut-out portion located inwardly of and adjoining said inwardly extending flap.

6. A container having a cover with a mutilatable display panel and a border therearound and having score lines connecting the corners of the cover with corresponding corners of said display panel to provide for flexing said border, panels connected to and forming extensions of said cover, an adjustable bottom connected to and forming an extension of one of said side panels adapted to act upon the contents of the container to raise said display panel above the outer edges of said cover, and a lining for said cover comprising a sheet fastened around said display panel to the inner sides of said border.

7. A container having a cover with a mutilatable display panel and a border therearound and having score lines connecting the corners of the cover with corresponding corners of said display panel to provide for flexing said border, panels connected to and forming extensions of said cover, an adjustable bottom connected to and forming an extension of one of said side panels adapted to act upon the contents of the container to raise said display panel above the outer edges of said cover, and a lining for said cover comprising a sheet of transparent material fastened to the inside of said cover by a strip of adhesive material substantially completely enclosing the figure formed by said display panel.

8. A container having a cover with a mutilatable display panel and a border therearound and having score lines connecting the corners of the cover with corresponding corners of said display panel to provide for flexing said border, panels connected to and forming extensions of said cover, an adjustable bottom connected to and forming an extension of one of said side panels adapted to act upon the contents of the container to raise said display panel above the outer edges of said cover, and a lining for said cover comprising a sheet fastened around said display panel to the inner sides of said border, and said border having a cut-out portion adjacent to a portion of the outer edges of said display panel.
